UNITED STATES PATENT OFFICE

155,973

DESIGN FOR A PLACE CARD HOLDER OR SIMILAR ARTICLE

Frank L. Danner, Medford, Mass.

Application June 10, 1948, Serial No. 146,878

Term of patent 14 years

(Cl. D44—24)

To all whom it may concern:

Be it known that I, Frank L. Danner, a citizen of the United States, residing at Medford, in the county of Middlesex, in the Commonwealth of Massachusetts, have invented a new, original, and ornamental Design for a Place Card Holder or Similar Article, of which the following is a specification, reference being had to the accompanying drawing, forming a part thereof, in which:

Figure 1 is a front elevational view, Figure 2 is a side elevational view and Figure 3 is a rear elevational view, Figure 4 is a top plan view and Figure 5 is a perspective view of a place card holder embodying my new design.

I claim:

The ornamental design for a place card holder or similar article, substantially as shown.

FRANK L. DANNER.
